UNITED STATES PATENT OFFICE.

WILLIAM G. SCHNEE, OF KANSAS CITY, MISSOURI.

CRIB ATTACHMENT FOR BEDSTEADS.

No. 887,529.

Specification of Letters Patent.

Patented May 12, 1908.

Application filed August 30, 1907. Serial No. 390,820.

To all whom it may concern:

Be it known that I, WILLIAM G. SCHNEE, citizen of the United States, residing at Kansas City, in the county of Jackson and State 5 of Missouri, have invented certain new and useful Improvements in Crib Attachments for Bedsteads, of which the following is a specification.

This invention has for its object a simple, 10 durable, and efficient construction of crib attachment for bedsteads, which may be easily connected to the side rail of a bedstead and held in an out-of-the-way position when not in use, the parts being so arranged 15 that the attachment may be swung outwardly from underneath the bedstead and easily secured in an operative position approximately level with the mattress of the larger bed.

20 With this and other objects in view as will more fully appear as the description proceeds, the invention consists in certain constructions, arrangements and combinations of the parts that I shall hereinafter fully describe 25 and then point out the novel features in the appended claims.

For a full understanding of the invention, reference is to be had to the following description and accompanying drawings, in which:

30 Figure 1 is a perspective view of a bedstead showing my improved crib attachment applied thereto and in an operative position; Fig. 2 is a similar view showing the invention applied to one side rail of the bed- 35 stead and in an inoperative position; Fig. 3 is a rear view of the attachment; Fig. 4 is a side elevation of one of the jointed supports therefor; Fig. 5 is an enlarged detail sectional view of the joint; and, Figs. 6 and 7 40 are detail side and end views of a modified form of clamp that may be employed.

Corresponding and like parts are referred to in the following description and indicated in all the views of the drawings by the same 45 reference characters.

Referring to the drawings, the numeral 1 50 designates a bedstead which may be of any desired form, size, and construction, the bedstead in the present instance being illustrated as of the metallic type, with angle iron side rails 2, to either one of which my improved crib attachment may be connected. The said attachment comprises a pair of clamps 3 of angular formation adapted to 55 embrace one of the side rails and be secured thereto at the desired point by means of a

binding screw, as shown. The vertical arm of each clamp 3 is extended upwardly, as indicated at 4, so as to form upright posts or standards. The upper ends of these standards are formed respectively with disk-like 60 heads 5 formed with upper and lower notches 6. Angular hanger arms 7 are pivotally connected at one end to the heads of the respective standards 4 so as to provide jointed 65 supports for the crib, said arms being preferably rigidly connected together by the cross bar 8. Latches 9 are carried by the respective arms 7 and are spring pressed into engagement with the upper or lower notches 70 in the heads 5, so as to hold the hanger arms in an upwardly extending position projecting above and outwardly from the side rail 2, or in an inoperative position extending downwardly and inwardly beneath the said side 75 rail. In order to simultaneously retract both latches, I may provide a cord 10 secured thereto, as clearly indicated in the drawings.

To the outer end of each hanger arm 7 a link 11 is pivotally connected at one end and is secured at its other end to the base portion or spring mattress frame 12 of the crib attachment.

13 designates guide rods that are pivotally 85 connected at one end to the ends of the said base portion and that are formed at their opposite ends with longitudinal slots 14 accommodating screws or studs projecting from the clamps 3.

15 and 16 designate, respectively, the ends and side of the crib attachment, the two ends being hinged to the base portion in a different plane from the side, so that the ends may be folded down upon the base portion and the 95 side then folded down upon the ends.

17 designates a pivoted leg connected to the crib attachment to assist in supporting the latter when it is in an extended or operative position. This leg may be swung upwardly against the inner side of the base portion 100 when not in use.

From the foregoing description in connection with the accompanying drawings, it is manifest that the crib attachment of my invention may be readily attached to either side rail of a bedstead and be easily swung out into the operative position illustrated in Fig. 1, and held securely in place by the latches 9 110 engaging in the upper set of notches 6, assisted if desired by the pivoted leg 17. When not in use, the crib may be easily moved to an

inoperative position, by releasing the latches 9 from the upper set of notches and swinging the entire attachment downwardly and inwardly underneath the side rail where it will be held out of the way and concealed by the counterpane, the latches taking into the lower set of notches in the heads 5 of the standards 4.

If the side rails of the bed are of what is known as the inverted type indicated at 2^a in Figs. 6 and 7, I may employ clamps 3^a provided with pivoted hooks 18.

Having thus described the invention, what is claimed as new is:

15 1. A crib attachment for bedsteads, comprising standards arranged to be secured to the side rail of a bedstead and to project upwardly therefrom, hanger arms pivotally connected at one end to the upper ends of the standards and arranged to swing downwardly and underneath the standards, links pivotally connected to the outer ends of said hanger arms to move in the same plane as said arms, a crib connected to and suspended 25 from said links, and means for holding the hanger arms in extended and folded positions relatively to the standards.

2. A crib attachment for bedsteads, comprising standards arranged to be secured to the side rail of a bedstead and to project upwardly therefrom, hanger arms pivotally connected at one end to the respective standards and arranged to swing downwardly and underneath the same, links pivotally connected to the outer ends of the hanger arms and movable in the same plane as said arms, a crib connected to and suspended from said links, guide rods connecting the crib to the standards, and means for holding the hanger 35 arms in extended and folded positions with respect to the standards.

3. A crib attachment for bedsteads, comprising clamps adapted to be secured to the side rail of a bedstead and embodying standards adapted to project upwardly from the 40

50 rail and formed with heads having upper and lower notches, angular hanger arms pivotally connected at one end to the respective heads, latches connected to the respective arms and designed to enter said upper and lower notches to hold the hanger arms in extended and folded positions, links pivotally connected at one end to the opposite ends of said hanger arms, and a crib attached to said links. 55

4. A crib attachment for bedsteads, comprising clamps adapted to be secured to the rail of a bedstead and having upwardly extending posts provided with heads formed with upper and lower notches, hanger arms 60 pivotally connected to said heads, latches carried by said arms and adapted to engage in the upper or lower sets of notches, links pivotally connected to the outer ends of said arms, a crib connected to said links, and 65 guide rods pivotally connected at one end to the ends of the crib and having longitudinally slotted opposite ends, the clamps being provided with studs received in the said slotted ends. 70

5. A crib attachment for bedsteads, comprising clamps designed to be secured to the rail of a bedstead and provided with heads formed with upper and lower notches, hanger arms pivotally connected to said heads, a cross bar connecting said arms together 75 for simultaneous movement, spring pressed latches adapted to enter the upper and lower notches and pivotally mounted upon the respective arms, a cord connected to both of 80 said latches whereby to simultaneously retract both of the latches and a crib pivotally suspended from the outer ends of said hanger arms.

In testimony whereof I affix my signature 85 in presence of two witnesses.

WILLIAM G. SCHNEE. [L. S.]
